UNITED STATES PATENT OFFICE.

FRANCIS I. DU PONT, OF WILMINGTON, DELAWARE.

MEANS TO PROTECT SUBMARINE-MINE FIELDS.

1,304,549.

Specification of Letters Patent.

Patented May 27, 1919.

Application filed April 4, 1917. Serial No. 159,647.

To all whom it may concern:
Be it known that I, FRANCIS I. DU PONT, a citizen of the United States, residing at Wilmington, county of New Castle, and 5 State of Delaware, have invented a new and useful Improvement in Means to Protect Submarine-Mine Fields, of which the following is a full, clear, and exact description, reference being had to the accompanying 10 drawings, which form a part of this specification.

My invention relates to the subject of naval defense and has especially for its object the safeguarding of certain water 15 fronts and marine highways in case of war. In such waters, mines and floating bombs are anchored at various points. These mines, though entirely invisible from the surface, are not submerged very deeply so 20 as not to be beyond the depth of the smaller craft of the enemy.

It is well understood in general how these mines are constructed and planted. An effective means used by an enemy to clear a 25 safe passage over such a mine protected area is to run over it two light draft vessels, in parallel lines, trailing a cable between them. The cable is allowed to sink deep enough to sweep against the anchor lines of the mines 30 in its path, and in this way the mines are dragged away from their anchorages. A mine field may be thus partly or wholly destroyed.

The object of my invention is to provide 35 means for nullifying this action of the enemy and protecting the mines. My invention consists of cable-severing mechanism attached to the mine anchor line below the mine, or preferably to a separately anchored 40 line contiguous to the mine, in such manner that the dragging cable of the mine-destroyers will engage said cutting mechanism and be severed thereby before it has a chance to work any substantial damage to 45 the mine field.

Embodiments of the invention are shown in the accompanying drawings, in which:—

Figure 1 is a view, partly in elevation and 50 partly in vertical section, of the shearing mechanism and the submerged anchored carrier therefor. Fig. 2 is a section on the line 2—2 of Fig. 1. Fig. 3 is an elevation of a modification. Fig. 4 is an enlarged vertical section along the shears of Fig. 3. 55 Fig. 5 is an enlarged cross section on the line 5—5 of Fig. 4.

The preferred embodiment of the invention, shown in Figs. 1 and 2, will be first described. The carrier or body *a* may represent one of the mines, but preferably it 60 represents an independent body, located in the mine field, and anchored in position by means of a cable *b* connected with an anchor or weight (not shown) at the bottom of the body of water.

Secured in one side of the body *a* is one jaw or blade *c* of a pair of shears. This jaw is preferably fixed and extends vertically. The other jaw *d* is pivoted, at its upper end, 70 to the body *a*. This jaw also extends downward but diverges somewhat from the fixed jaw. The space between the cutting edges of the jaws is open at the bottom and closed at the top.

The pivoted jaw *d* has an inwardly disposed arm *e* which engages a piston or plunger *f* in a piston chamber *g*, the space beneath the piston acting as a container for explosive material. A spring-actuated firing pin *h* is restrained from operation by 80 means of its engagement with one arm of a bell-crank lever *i* pivoted in a recess in the body *a*. The other arm of the bell-crank extends into the space between, or in line with the space between, the cutting jaws. 85 To exclude the entrance of moisture to the powder charge, and also to protect the jaws of the shears from corrosion, a very thin copper sheathing *j* (indicated in dotted lines in Fig. 1) incloses the movable jaw, 90 covers the projecting edge of the fixed jaw and incloses the space at the root of the jaws communicating with the explosive charge and its firing mechanism. This copper sheathing is readily severed when the 95 jaws of the cutter close, but tends to hold them in open position until they are positively actuated.

The upper part of the body *a* is bulbous shaped, affording sufficient air space to float 100 the mechanism, while the lower part is tapered downward, presenting an upwardly and outwardly extending inclined surface leading to the space between the jaws.

It is desirable to provide a plurality of 105 shearing devices located at different points about the circumference of the body *a* so that, in the event that a dragging cable engages the cable *b* it will with certainty be directed into the space between one pair of 110 jaws. As soon as such dragging cable strikes and tilts the lever *i*, the latter re-

leases the firing pin *h*, which ignites the powder charge. The explosion forces the plunger *f* against the arm *e*, thereby swinging the jaw *d* toward the jaw *c* and severing 5 the dragging cable.

- In the embodiment of the invention shown in Figs. 3, 4 and 5, the dragging cable itself supplies the force required to operate the shears. The latter consist of 10 two shearing jaws or blades *m* and *n*, one carried by the body *o* and the other by a holder *p* secured at its upper end to the body *o* and thence extending down alongside of, but diverging somewhat outwardly 15 from, the wall of the body *o*. Preferably both jaws are movable, and preferably, also, both jaws are arranged to slide upwardly, thus causing opposing points on the two jaws to approach each other. The sliding 20 movement of the jaws is facilitated by causing the inner longitudinal edges of the jaws to travel in elongated recesses in contact with rollers *r* rotatable on the bottoms of the recesses.
- 25 It is obvious that if a dragging cable, by its contact with the anchorage cable, is guided into the space between any two jaws *m* and *n*, it will, by virtue of its own pulling force, draw the jaws upwardly and 30 therefore cause them to sever the dragging cable.

A plurality of shears *m*, *n*, are provided about the periphery of the body *o*, as in the case of the pivoted shears before described, 35 and also similar to that case shears *m*, *n*, are entirely covered and protected by thin copper shell indicated at *s* to preclude corrosion.

Having now fully described my invention, what I desire to claim and protect by Letters Patent is:—

1. Means to protect submarine mine fields comprising a submersible body, an anchorage cable to which the body is secured, and 45 cutting means positioned and adapted to sever any dragging cable that engages the anchorage cable and is guided thereby relatively upward toward the cutting means.
2. Means to protect submarine mine fields 50 comprising a body adapted for submergence beneath the surface of the water, an anchorage cable to which the body is secured, and shears the jaws of which open downward in position to engage any dragging cable

that engages the anchorage cable and is 55 guided thereby into the space between the jaws.

3. Means to protect submarine mine fields comprising a body adapted for submergence beneath the surface of the water, an anchorage cable secured to the body, shears carried by the body the jaws of which open downward toward the anchorage cable whereby the dragging cable is guided upward between the jaws, and means controlled by the dragging cable to effect a relative approach of the jaws to sever the driving cable.

4. Means to protect submarine mine fields comprising a body adapted for submergence 70 beneath the surface of the water, an anchorage cable secured to the body, shears carried by the body the jaws of which open downward toward the anchorage cable whereby the dragging cable is guided upward between the jaws, a container for an explosive charge, means operable by the dragging cable to explode the charge, and means operable by the explosive charge to cause a relative approach of the jaws of the 80 shears to sever the dragging cable.

5. Means to protect submarine mine fields comprising a body adapted for submergence beneath the surface of the water, shears, and a relatively thin and readily severable 85 protective sheathing for the shears.

6. Means to protect submarine mine fields comprising a body adapted for submergence beneath the surface of the water, and a plurality of shears each of which is adapted 90 to sever a dragging cable, said shears being arranged along the outside of said body on different radii of the body's vertical axis.

7. Means to protect submarine mine fields comprising a submersible body having a 95 cone-shaped lower end, and a pair of shearing jaws one of which substantially aligns with the tapered side of the lower end of the body, while the other of which extends downward alongside the body and spaced 100 from the other jaw, whereby a dragging cable contacting with the lower end of the body will be guided upward between the jaws and severed.

In testimony of which invention I have 105 hereunto set my hand, at Philadelphia, on this 2nd day of April, 1917.

FRANCIS I. DU PONT.
